POWER OPERATED MUSICAL INSTRUMENT

Filed Dec. 28, 1926

Mr. Otis O. Fusch
by W. H. Maxwell
his Attorney

UNITED STATES PATENT OFFICE.

OTIS O. FUSCH, OF BELLFLOWER, CALIFORNIA.

POWER-OPERATED MUSICAL INSTRUMENT.

Application filed December 28, 1926. Serial No. 157,463.

This invention has to do with a musical instrument and has particular reference to a power operated musical instrument.

Xylophones, orchestra bells, and various other like and similar musical instruments such as are commonly used in orchestras, are difficult to play, as the sounding members must be rapidly and uniformly struck by means of hammers, or the like. The proper 10 operation of hammers employed in playing these instruments requires extensive practice.

It is an object of my present invention to provide a device for playing orchestra bells or other similar musical elements whereby the 15 elements are struck with the desired rapidity and regularity through depression of suitable control keys.

It is an object of my invention to provide an instrument of the character mentioned, which 20 is simple and compact, making it suitable for use in orchestras and the like where it is necessary that the instruments be portable.

It is another object of my invention to provide an instrument of the character mentioned, which can be operated at the will of 25 the operator to strike the sounding members at various speeds.

Another object of my invention is to provide an instrument of the character described, 30 with an extremely simple, effective and inexpensive movement, or key controlled mechanism.

The various objects and features of my present invention will be best and more fully understood from the following detailed description 35 of a typical form and application of the invention, throughout which description reference is had to the accompanying drawings, in which:

Fig. 1, is a top or plan view of my improved instrument showing it with the top or upper portion of the casing removed;

Fig. 2, is a detailed, transverse, sectional view of the instrument taken as indicated by 45 line 2—2 on Fig. 1;

Fig. 3, is a detailed plan view of a portion of the instrument, being a view taken as indicated by line 3—3 on Fig. 2;

Fig. 4, is an enlarged sectional view of a 50 portion of the instrument, being a view taken as indicated by line 4—4 on Fig. 2; and

Fig. 5 is an enlarged view, illustrating the

movement or striking mechanism provided by my invention.

My present invention may be employed or 55 carried out with sounding elements of various kinds and I may state for example, that the invention may be employed to actuate the sounding elements of orchestra bells, xylophones, or the various elements of traps employed in bands, orchestras, etc. In this connection, it is to be understood that the invention may be carried out to actuate a combination of different types of sounding elements. For purpose of example, I will refer to the invention as being applied to the actuation of 60 orchestra bells as such elements present a typical condition that can be advantageously handled by my present invention.

The device embodying my invention includes, generally, the striking mechanism 12, operable to actuate the elements 11, drive means 13 which actuates the power operated element of the striking mechanism, and various other parts and features, the details of 65 which will be hereinafter described.

The casing 10 includes, generally, a main compartment A, which carries the sounding elements 11, a key compartment B at which is located the control keys 15, and a drive compartment C, which carries the drive means 13. The main compartment A, is shaped and proportioned to properly accommodate the 70 sounding elements 11, and in any particular case, the shape and size of this compartment 80 will depend upon the number, size, arrangement, and character of the sounding elements.

It is preferred however, in practice, to arrange the parts within the compartment A, so that they are as compact as possible. One part, for 85 instance, the top of the compartment A, is formed with a hinged portion or section 17, adapted to be opened and closed to control the volume of sound from the instrument. In practice, I may line the compartment A, and if desired the compartment C, with sound deadening material, such as felt or the like. The key compartment B is located at the front 90 of the compartment A, and has a plurality of control keys 15 projecting into it from the compartment A. The front 16 of the compartment B is mounted on hinges 17a or in any other suitable manner so that it can be removed or swung out of position at the front 95 100

of the compartment B, making the keys 15 accessible for operation. The drive compartment C, may be located at one end of the compartment A, to carry the various parts or drive means 13 as will be hereinafter described. The casing 10, may be provided with supporting legs 10^a or it may be added to or made a part of some other instrument.

The sounding elements 11, illustrated in 10 the drawings are in the nature of orchestra bells and for purpose of compactness, I have arranged them in two series, and have spaced the two series, one above the other, in the compartment A. The lower series of bells 11, 15 is carried by or suspended from suitable carriers 20, which extend between the ends 70 and 71 of the compartment A. The upper series of bells is supported a substantial distance above the lower series and is carried by 20 or suspended from the carriers 21, which extend between the ends of the compartment A. The general arrangement of the bells in the compartment A, will be understood from inspection of the Figs. 1 and 2, of the drawings. 25 The striking mechanism 12, includes, generally, a rod 23 located between the two series of bells and extending parallel with the series of bells between the ends 70 and 71 of the compartment A, levers 24, mounted on the rod, keys 15 mounted on a rod 25, hammers 26 carried by the levers, connections 27 between the keys and levers, and a power operated member 29 for actuating or oscillating the levers. The principle of construction and 30 operation employed in striking each key being the same, I will proceed to describe one single mechanism, it being understood that the description applies to all.

The lever 24 is freely carried on the rod 23, 40 at a point substantially opposite the bell to be played, while the key 15 for operating the lever 24 is freely carried on the rod 25 at a point opposite or substantially in line with the lever 24. The key 15 extends forward 45 from the rod 25 to project from the compartment A into the compartment B where it can be engaged by the operator. The key is normally held in the up position by a suitable spring 30. The upward movement of the key 50 may be limited by the lower edge 31 of the partition 32 which separates the compartments A and B. The operating connection between the lever 24 and key 15 extends downwardly from one end of the lever and 55 connects with the key at a point removed from its pivotal mounting. The connection includes a resilient element, for instance, a spring 33. A second spring 34 is arranged in connection with the lever 24, for instance, 60 under its other end, to counteract or urge the lever in the direction opposite to the direction to which it is urged by the spring 33. The springs 33 and 34 are balanced or related so that the lever 24 is held in the position shown in Fig. 2 when the key 15 is in the

normal unactuated position. When the key is actuated or depressed, the connection 27 causes the lever 24 to be operated or moved to the operated position. The hammer 26 includes a spring arm 38 extending from the lever 24 and a head 39 carried on the outer part of the arm. The arm 38 is shaped and proportioned so that the head 39 is carried in position to strike the bell when the device is operated as hereinafter described. The power operated element or member 29 is in the form of a cam extending parallel with the rod 23 at a point to be engaged by the lever when the lever is moved to the down position. The cam 29 is rotated through the drive means 13 hereinafter described, and is shaped, for instance, as shown in the drawings, so that it oscillates or vibrates the lever when the parts are in operating position. In the arrangement shown, the head 39 is normally spaced from the bell, but when the arm 24 is oscillated or vibrated, the resiliency of the arm 38 allows the head to strike the bell. The rate at which the bell is struck by the hammer will, of course, depend upon the speed at which the cam 29 is driven. The cam 29 is carried by or between suitable bearings 40 at the ends 70 and 71 of the compartment A, and thus extends past all of the levers 24 to operate any lever that may be depressed through depression of its corresponding key.

The drive means 13 provided for actuating the cam is located in the compartment C, and includes, generally, a source of power such as a motor M, a shaft 45, which extends into the compartment C from or as, a continuation of the cam, and a variable speed drive between the motor M and shaft 45. In practice, I have found it advantageous to employ a friction drive, and in the arrangement shown in the drawings, I drive a friction disk 46 from the motor through a suitable belt 47 and I provide a friction wheel 48 on the shaft 45 to engage the face of the disk. The friction wheel 48 may be slidably keyed to the shaft 45 and may be shifted with reference to the disk through a rod 49 which carries an arm 50 engaging the hub of the wheel 48. A spring 51 may be arranged in connection with the disk 46 to urge it toward the wheel 48 to maintain the disk and wheel in driving contact. It will be obvious that shifting of the wheel to various positions on the disk will vary the speed at which the cam is driven. The rod 49 by which the wheel is shifted may be operated from any convenient point, for instance, from a point at the front of the casing 10 immediately below the key board of the instrument. In the drawings, I have shown a lever 55 operatively connected with the rod 49 and having one end at the exterior of the instrument immediately below the key board.

It is desirable to provide means for con-

veniently operating the movable top part 17 of the compartment A, and for this purpose I may provide a lever 60 having one end accessible from the exterior of the device adjacent 5 the key board and the other end operatively connected with the part 17 by a rod 62.

In carrying out my invention I may increase the size or range of the instrument by adding additional units of sounding elements 10 to the end 71 of the casing 10. These additional units may include striking mechanisms and the cams of such mechanisms may be attached to the cam above described so that the whole instrument is operated from the 15 means 13.

In operation, the motor may be operated continuously, it being preferred to employ a constant speed motor. The motor is preferably under control of a switch having an 20 operating part 80 located adjacent the key board. With the motor in operation, the cam 29 is driven through the drive above described. When it is desired to strike one of the bells, its corresponding key is depressed, 25 causing its lever 24 to be moved down into engagement with the cam so that the cam trips or vibrates it, resulting in the vibration of the hammer carried by the said lever so that the hammer strikes the bell. The 30 speed at which the hammer is vibrated, or in other words, the speed at which the bell is struck will depend upon the speed of rotation of the cam, this being under control of the operator through the control lever 55, 35 which is connected with the shiftable friction wheel 48. In view of the fact that all of the levers 24 are in position to be engaged by the cam 29, all notes or bells played simultaneously will be struck at exactly the same 40 rate. I have found in practice, that the variable speed control makes it possible for an operator to very easily control the speed at which the notes are struck, and it is possible to manipulate the controls to obtain very 45 pleasing results.

Having described only a typical preferred form of my invention, I do not wish to limit myself to the specific details set forth, but wish to reserve to myself any changes or 50 variations that may appear to those skilled in the art or fall within the scope of the following claims.

Having described my invention, I claim:

1. A musical instrument including a sound- 55 ing element, a hammer unit operable to strike the element, the hammer unit including a pivoted lever and a spring arm directly attached to the lever, a continuously operating cam, and control means whereby the hammer 60 and cam unit are directly related so that the cam directly engages the lever causing the hammer to strike the element.

2. A musical instrument including a 65 sounding element, a hammer, a cam, power

means for continuously operating the cam, 65 means for varying the speed of operation of the cam, and control means whereby the hammer is moved with relation to the cam so that the cam operates the hammer to strike the element. 70

3. A musical instrument including a sounding element, a hammer, a continuously operating cam, and control means whereby the hammer and cam are related so that the cam operates the hammer to strike the element, 75 said control means including a lever carrying the hammer, a key, and a direct connection between the lever and key whereby operation of the key moves the lever into position to be directly engaged by the cam. 80

4. A musical instrument including a sounding element, a hammer, a continuously operating cam, and control means whereby the hammer and cam are related so that the cam operates the hammer to strike the element, 85 said control means including a lever carrying the hammer, a key, and a direct connection between the lever and key whereby operation of the key moves the lever into position to be directly engaged by the cam, 90 said connection including a spring.

5. A musical instrument including a sounding element, a hammer unit, a continuously operating cam, and control means whereby the hammer and cam unit are related 95 so that the cam directly operates the hammer to strike the element, the hammer including a pivoted lever directly engaged by the cam, a spring arm having its inner end attached to the lever, and a head carried by the outer 100 part of the arm.

6. A musical instrument including a sounding element, a hammer, a continuously operating cam, and control means whereby the hammer and cam are related so that the cam operates the hammer to strike the element, 105 said control means including a lever carrying the hammer, a key and a connection between the lever and key whereby operation of the key moves the lever into position 110 to be engaged by the cam, the hammer including a spring arm carried by the lever and a head on the outer part of the arm.

7. A musical instrument including, a sounding element, a hammer, a rotating cam 115 for operating the hammer, and means for operating the cam including, a motor, and a variable speed drive between the motor and cam.

8. A musical instrument including, a 120 sounding element, a hammer, a rotating cam for operating the hammer, and means for operating the cam including, a motor, and a variable speed drive between the motor and cam including a friction disk driven by the 125 motor and a friction wheel connected with the cam and movable to engage different parts of the disk.

9. A musical instrument including a case having three compartments, a sounding element in one compartment, means for striking the element including a cam in said compartment and a key in one of the other compartments, variable speed operating means for the cam and located in the third com-

partment, and means whereby the operating means is controllable from a point adjacent the key.

In witness that I claim the foregoing I have hereunto subscribed my name this 20th day of Nov. 1926.

OTIS O. FUSCH.
